Primary Examiner—Celia Murphy*Attorney, Agent, or Firm*—Marshall A. Lerner, Esq.; Bradford E. Mattes, Esq.; Kleinberg & Lerner, LLP**[57] CLAIM**

The ornamental design for a combined shoe bottom and periphery, as shown and described.

DESCRIPTION

FIG. 1 is a perspective view of the left and bottom of a combined shoe bottom and periphery showing my new design;

FIG. 2 is a bottom plan view thereof;

FIG. 3 is a right side elevational view thereof;

FIG. 4 is a left side elevational view thereof;

FIG. 5 is a front elevational view thereof; and,

FIG. 6 is a rear elevational view.

The broken line showing of the shoe upper in the figures is for illustrative purposes only and forms no part of the claimed design. In, addition, the top surface of the sole in FIGS. 5 and 6 are left unshaded because they are not part of the claimed design.
